UNITED STATES PATENT OFFICE.

GEORGE FRANCIS BOES, OF LA FAYETTE, INDIANA.

TILE-MAKING MACHINE.

Application filed February 13, 1924. Serial No. 692,467.

To all whom it may concern:

Be it known that I, GEORGE FRANCIS Boes, a citizen of the United States, residing at La Fayette, in the county of Tippecanoe and State of Indiana, have invented a certain new and useful Improvement in Tile-Making Machines, of which the following is a full, clear, concise, and exact description, reference being had to the accompanying drawings, forming a part of this specification.

My invention relates to machinery for making tiles, building blocks and the like.

One of the objects of the invention is to provide a simple and practical apparatus of the class specified.

Another object of the invention is to provide a construction which is particularly advantageous for the making of building tiles or blocks having certain features of construction particularly adapting them for drainage purposes.

Another object of the invention is to secure the foregoing and other desirable results in a simple and expeditious manner.

In the accompanying drawings Fig. 1 is a vertical section of a tile or block machine or apparatus embodying my invention;

Fig. 2 is a horizontal section of the same taken on line 2—2 in Fig. 1;

Fig. 3 is a perspective view of a portion of the apparatus;

Fig. 4 is a view of the tile or block made by the machine;

Fig. 5 is a view of a detail of construction; and

Fig. 6 is a cross sectional view similar to Fig. 1 of a modified form of machine.

Referring to the drawings, the apparatus shown comprises a base 1 and a form 2 resting thereon, together with side walls 3 and 4 and end walls 5 and 6, which walls rise from the base 1. The form 2 is shown by itself in Fig. 3, and is preferably made in the form of a semi-cylindrical shell, as shown in said Fig. 3, with small end flanges 6^a—6^a to hold said form firmly in place. Said form is also preferably provided with downwardly extending flanges or projections 7—7 which are adapted to fit into recesses or apertures 8—8 in a plate 9 which rests on the base 1, said members 7—7 serving to hold the form 2 against lateral or sidewise movement. The form 2 is also preferably provided with an upwardly extending projection 10 made with inclined

side and end walls 11 and 12, respectively, the purpose of this projection 10 being pointed out hereinafter.

The end walls 5—6 are preferably held in position by being hinged at their lower edges on pivot rods 13—13, so that they may be swung up and down to close and open the mold or chamber in which the block or tile is to be formed. Handles 14—14 keep the end walls or doors 5 and 6 in upward position to maintain the mold closed. Inner wall members or linings 16—16 are secured, as by bolts 16^a—16^a to the walls or doors 5 and 6, and these members 16—16 are provided with apertures 16^b—16^b, to accommodate the ends of form 2.

A vertically movable or reciprocating piston 17 is provided with plungers 18—18 arranged to move up and down above the form 2 but said plungers do not move quite far enough to contact with form 2, as shown in Fig. 1.

The apparatus thus described will form a block having certain drainage features, which block is shown in cross section in Fig. 4 and is shown and described and claimed in my application for United States Letters Patent Serial No. 687,169, filed January 19, 1924. Said block involves side walls 19—19 forming between them a horizontally extending recess 20 which forms a drainage duct or passage by which water may be drained horizontally by means of said tile and a plurality of such tiles arranged end to end. Said block also has a transverse wall 21 above the drainage duct 20, which transverse wall forms a shelf to catch mortar falling down from above, and so protects the drainage duct 20 from being clogged or filled by mortar or other matter. The shelf 21 is divided horizontally so as to form an intermediate space, as shown in Fig. 1, and this space forms a vertical or top opening into the drainage duct 20, by which water or other liquid may drain down into the drainage duct while mortar and other solid matter is caught by shelf 21.

Referring now to my apparatus, it will be seen that the form 2 forms a recess or drainage duct 20 and the projection 10 forms an opening or space communicating with the top of the drainage duct to afford water or liquid inlet into the same. It will also be seen that the side walls 19 are formed by the plungers 18—18 and the side and end walls 3, 4, 5 and 6 previously described.

- Thus by filling a proper amount of cement or concrete or other matter into the apparatus and then lowering the piston 17 so as to lower the plungers 18, the drainage block 5 previously described will be formed with its bottom, horizontal drainage passage, its shelf for mortar and the like, and its opening from above into the drainage passage so as to permit liquid to flow into the same.
- 10 In Fig. 6 I show a modified form of apparatus in which there are three plungers 18^a, 18^a, and a form 2^a having projections 10^a, whereby there is formed a drainage block or tile with two top openings into the 15 drainage passage.
- It will be understood that changes and modifications may be made without departing from the spirit of the invention.
- What I claim is;
- 20 1. A machine of the class specified, comprising means for forming a block or tile with a laterally extending drainage passage and means for forming a shelf for collection of mortar or other solid matter to prevent 25 same having access to the drainage passage, and also for forming an aperture or opening into said drainage passage.
2. An apparatus of the class specified, comprising means for forming a laterally 30 extending drainage passage and means for forming a top or cover to said passage which top or cover forms a shelf for mortar or the like, and also means for forming an aperture through said top or cover to provide a 35 liquid inlet into said drainage passage.
3. An apparatus of the class specified, comprising means for forming a closed space for a tile or block and an arched form at the bottom of said space for forming a drainage 40 passage in said tile or block, said form being provided with an upwardly extending projection to form an aperture into the duct or passage formed by said arched form, and plungers for forming cavities above said 45 form, which cavities communicate with said aperture formed by the projection on said form.
4. An apparatus of the class specified, comprising a base, side and end walls, and 50 an arched shell mounted on said base and adapted to form a drainage passage in the block or tile formed by said side and end walls, said shell having an upwardly extending projection adapted to form an opening into the drainage passage formed by said shell, and plungers arranged above said form and adapted to provide spaces in the block or tile which communicate with the opening formed by said projection on said shell.
5. An apparatus of the class specified, comprising a base, side and end walls, and an arched shell mounted on said base and adapted to form a drainage passage in the block or tile formed by said side and end walls, said shell having an upwardly extending projection adapted to form an opening into the drainage passage formed by said shell, plungers arranged above said form and adapted to provide spaces in the block or tile which communicate with the opening formed by said projection on said shell, and means on said shell for holding the same in position.
6. An apparatus of the class specified, comprising a base, side and end walls, and an arched shell mounted on said base and adapted to form a drainage passage in the block or tile formed by said side and end walls, said shell having an upwardly extending projection adapted to form an opening into the drainage passage formed by said shell, plungers arranged above said form and adapted to provide spaces in the block or tile which communicate with the opening formed by said projection on said shell, and means on said shell for holding the same in position, said means comprising laterally extending flanges 6 and downwardly extending 75 projections 80.
7. An apparatus of the class specified, comprising a base, an arched shell mounted on the base, side and end walls at the sides and ends respectively of said form, said end walls being provided with apertures to accommodate the ends of the form, said form being provided with an upwardly extending projection rising from its upper portion and a piston having plungers adapted to make contact with said projection on said form.
- In witness whereof, I hereunto subscribe my name this seventh day of February, A. D., 1924.
- GEORGE FRANCIS BOES.
